REFRIGERATOR CONTROL

Edward R. Taylor, Rocky River, and Donald P. Armbruster, Cleveland Heights, Ohio

Application October 31, 1946, Serial No. 706,918

5 Claims. (Cl. 62—7)

1

This invention relates to improvements in refrigerator controls especially that type utilizing a liquid refrigerant adapted to be vaporized.

An object of the present invention is to catch the liquid refrigerant as it enters the vaporizing space and to utilize the weight of the liquid refrigerant to control the opening and closing of the refrigerant admission valve.

Another object of the present invention is to provide novel means for counterbalancing the weight of the liquid refrigerant in the vaporizing chamber so that a very exact balance is obtained at all times, resulting in a nice adjustment of the refrigerant admission valve.

Our invention also provides novel means for insuring the automatic separation of the refrigerant from oil carried over from the compressor operation. This includes novel means for insuring that oil or other liquid is returned to the compressor in sufficiently small increments so as to cause no damage to the compressor.

One of the advantages of our invention is its application to a beverage cooler, and therefore, our invention comprehends the placing of the beverage refrigerating coils within the liquid refrigerant reservoir. Where the beverage is beer, our invention includes the novel combination of a carbonator in combination with the cooler.

Our invention also contemplates the application of the novel vaporizing chamber directly in a space to be refrigerated so that the refrigerating effect occurs outside of the housing rather than inside the same as in connection with a beverage cooler.

Our invention also contemplates the use of a single reservoir or container for both the liquid and vaporized refrigerant and the utilization of the weight of this container to operate the refrigerant control valve directly. Since the use of such a container directly exposed to a refrigerated space will result in the accumulation of frost on the outer walls of the container, and since this will increase the weight of the container, we make use of this novel combination to provide automatic defrosting.

Another object of the present invention is to so multiply the forces acting in opposite directions on the refrigerant container as to provide an efficient control even against resistant forces, such as flexible connections and the like, which might otherwise prevent the efficient operation of our device.

Still another object of our invention is to provide a mechanical advantage for the weight of the liquid refrigerant whereby the efficiency of our device is improved.

2

A still further use of our invention is found in the combination of a single control device in combination with a plurality of cooling chambers whereby one device controls a plurality of chambers.

Other objects of our invention are the provision of a novel vapor space about the liquid refrigerant so as to reduce the radiation loss, and other novel combinations of structural features for carrying out the above-described purposes of our invention.

In the drawings,

Fig. 1 is a central sectional view through one embodiment of our invention, this view being taken along the line 1—1 of Fig. 2;

Fig. 2 is a top plan view of the device of Fig. 1;

Fig. 3 is a fragmental sectional view taken along the line 3—3 of Fig. 5;

Fig. 4 is a fragmental sectional view taken along the line 4—4 of Fig. 3;

Fig. 5 is a sectional view taken along the line 5—5 of Fig. 1;

Fig. 6 is a view similar to a portion of Fig. 1 and illustrating a modified form of our device;

Fig. 7 is another view similar to Figs. 1 and 6 and showing still another modification of our device;

Fig. 8 is a view of another modification of our device wherein both the liquid and vaporized refrigerant are in a single container, and the weight of this container is utilized directly to open and close the refrigerant admission valve;

Fig. 9 is another modification of our device wherein the refrigerant container is subjected to relatively strong forces acting in opposite directions so that lesser forces, such as the resistance of flexible tubes, may be readily overcome to provide efficient controlling operations;

Fig. 10 is a further modification of our invention wherein the refrigerant container is given a mechanical advantage so as to more efficiently control the refrigerant admission valve;

Fig. 11 is a further modification of our invention wherein a single control device provides control means for a plurality of cooling chambers; while

Fig. 12 is a further modification of our invention wherein the refrigerant admission valve is operated by snap action.

Referring first to Figs. 1 to 5 inclusive, we have illustrated one form of our invention wherein within a cooler 10 we have mounted the housing 11 providing a vaporizing chamber for a liquid refrigerant of the order of methyl chloride, although it will be understood by those skilled in this art that other vaporizable refrigerants might

be used. Our apparatus is intended to be used with a well known system, not shown, wherein a compressor withdraws vaporized refrigerant from the housing 11 and compresses the same, after which, it is cooled and condensed, and the liquid refrigerant is returned to the vaporizing chamber. Such systems are well known. The liquid refrigerant comes from the compressor through line 12 and a screen filter 13 to a volume control valve 14 and then to a refrigerant admission valve 15. The liquid refrigerant flows through the openings 15a and then through the tube 16 to a reservoir 17 which is mounted for vertical movement inside the housing 11. This reservoir is in the form of a cup, open at the top, although other forms of our invention do not require this cup shape, as will later appear. The liquid refrigerant normally fills the reservoir up to a predetermined level, such as the dash-dot-dot-dash line A which is determined by factors later described. As the refrigerant is vaporized to produce the desired cooling effect, it fills the upper portion of the cup, the annular space 18 around the sides of the reservoir and the space 19 below the reservoir. Through an outlet pipe 20 the vaporized refrigerant is carried back to the compressor, and this line contains a constant pressure valve 21 so as to hold the desired pressure inside the housing 11, as is customary.

The mounting of the reservoir 17 for vertical movement is accomplished in the present instance by arranging a central sleeve-like column 17a integral with the reservoir and liquid tight. Inside of this column is a sleeve 22 which is fixed to the base of the housing 11. The members 17a and 22 thus guide the reservoir for its normal slight movement in a vertical direction. In this form of our device a spring 23 within the sleeve 22 presses a thimble 24 against the upper end of the column 17a so as to counterbalance the weight of the liquid refrigerant in the reservoir. This spring is held in place by the screw 25 which may be arranged to give an adjustment of spring tension, if necessary or desirable. An operative connection between the floating reservoir and the valve 15 is provided whereby as liquid refrigerant is vaporized, the reservoir will rise, urged by the spring 23, and this motion is utilized to open the valve 15 to admit more liquid refrigerant. When enough refrigerant has entered to cause the reservoir 17 to again move downwardly, compressing spring 23, valve 15 will again be closed. This operative connection comprises a lever 26 having one end housed in a pocket 27 secured to the top of the column 17a. This lever has a pivot at 28 intermediate its ends which is fixed relative to the housing 11, as by means of the bracket 29. The other end of the lever is pivotally connected at 30 to the valve operator 31 extending upwardly through tube 16 and pivotally mounted at 32 on the valve 15. A compression spring 33 normally urges valve 15 in a valve opening direction. It will be noticed that the lever arm 28-30 is much shorter than the lever arm from 28 to the bearing member 34 in the pocket 27. This gives a greater mechanical advantage in favor of the reservoir whereby the weight of the reservoir is multiplied many times to give effective closing movement of valve 15.

In adapting our device specifically for the cooling of a beverage, for instance beer, we have illustrated the positioning of the beverage cooling coils directly in the liquid refrigerant inside the reservoir 17. The warm beer is introduced

through pipe 35 which enters the housing 11 through a suitable fitting 36 shown in Fig. 2, but omitted from Fig. 1 for clearness. This is connected with pipe 37 inside the housing 11 and extending downward through the open top of the cup shape reservoir 17. The outermost beer cooling coil 38 is a double coil, the lower ends of which are connected by a hairpin turn 39 indicated in dot-dash lines in Fig. 1. It results from this construction that the beer flows spirally downwardly through alternate coils 38a and returns spirally upwardly through the other turns 38b. As shown at the upper left-hand corner of this outer coil, it is connected as indicated in dot-dash lines at 40 with the intermediate beer cooling coil 41. The beer then flows spirally downwardly again and then through a connection indicated in dot-dash lines at 42 to coil 43. The beer then returns upwardly to the outlet line 44 which extends out through the top of the cup and through a fitting 45 (Fig. 2) to a line 46 which leads to the top of the carbonator 47. The outlet from the carbonator is through line 48 to a beer faucet 49. The nature of this carbonator will be better understood from a reference to Patent No. 2,125,248, granted July 26, 1938, to Edward R. Taylor.

A second coil for the cooling of water or the like is indicated. The warm water enters through line 50 and then through connection 51 on the top of housing 11, as indicated in Fig. 2, but this is omitted from Fig. 1 for clearness. The water passes downwardly through coil 52 and returns upwardly through coil 53 and then passes out through pipe 54 to a water faucet 55. It will be noted in Fig. 1 that the beverage coils are suitably suspended in a stationary condition by the use of one or more brackets 56 secured to the pocket 57 which is integral with the housing 11. It is thus possible for the reservoir 17 to move upwardly and downwardly, as indicated by the dot-dash lines of Fig. 1 without disturbing the beverage cooling coils.

It will be noted that the carbonator 47 is, to a large extent, housed within the pocket 57, all sides of which are subject to the cooling action of the refrigerant. We are thus enabled to keep the carbonator cold at all times, which is of great advantage when the apparatus has stood unused for a period of time, such as overnight. The carbonator usually holds four or five cups of beer and therefore, the first beer drawn in the morning is cold.

It should be noted in Fig. 1 that there is an annular space between the recess 57 and the upper rim of the reservoir 17. This provides an upwardly attenuated area so that the liquid refrigerant, in boiling, does not easily splash out the top of the cup-shape reservoir.

We have provided automatic means for eliminating the oil which normally floats on the liquid refrigerant. To this end, we have provided an opening 58 through the wall of reservoir 17 slightly above the normal level A of the liquid refrigerant. The oil carried over from the compressor is lighter than the liquid refrigerant and floats on top of the same. Thus, it will take a slightly greater volume of refrigerant plus oil to balance spring 23 than would be the case if there were refrigerant only in the reservoir. In other words, when there is oil on top of the refrigerant, it raises the level A slightly, whereupon the oil drains out the opening 58 and falls to the bottom chamber 19 whence it is carried back to the compressor. Obviously, if other advantages were

foregone, the rim of the cup 17 might be placed at about the level of the hole 58 so that oil would drain over the top of the cup. It is within the scope of our invention to drain the oil either over the rim of the cup or through an opening in the wall of the cup.

We have provided a novel construction where the vapor leaves the housing 11 to enter the line 20 for its trip back to the compressor so as to insure that at no time will a large amount of liquid be pumped back to the compressor so as to cause possible damage. This construction is most clearly shown in Figs. 3 and 4. Where the line 20 is connected with the container 11 for the removal of vapor therefrom, we have provided a baffle 59 which is in sealed relation to the container 11 above the line 20 and partly down the sides thereof, the baffle ending at a level slightly above the bottom of the container 11 within the space 19. This insures that the stream passing out the pipe 20 is continuously drawn from near the bottom of the space 19 and any small amounts of liquid such as oil or splashings of liquid refrigerant will immediately be picked up and taken away through pipe 20 so that only small amounts of liquid can be carried at any one time back to the compressor.

In Fig. 6 we have shown a further modification of our invention utilizing a weight in place of spring 23 for counterbalancing the refrigerant container. All of the parts of Fig. 6 which are like Fig. 1 and have the same function have been given the same reference characters and need not be further described here. The changes involved comprise the omission of spring 23 from the interior of sleeve 22. Instead, the bracket 27 has been extended as indicated at 27' to provide a bearing for the shorter arm of lever 60 which is pivotally mounted at 61 on the fixed bracket 62. The longer arm of lever 60 is engaged at the point 63 by a counterweight in the holder 64 which is supported for free vertical movement in the sleeve 65. The holder 64 may be filled with any suitable material for providing the desired weight needed to counterbalance the container 17 along with its contents and connections. For instance, the holder 64 might be filled up to the level indicated by line 66 by liquid such as mercury or solid material such as shot, weights, or the like. They may be adjusted to any point desired.

The operation of the device of Fig. 6 is quite similar to that of the first described form. As the refrigerant within the container 17 vaporizes, the container becomes lighter so that the counterweight applied at the point 63 is adapted to lift the container which in turn causes the lever 26 to move slightly in a counterclockwise direction about its pivot point 28 so as to move the valve operator 31 downwardly and to open the needle valve 15 which is connected to the upper end of the rod 31 as previously described. This will admit more refrigerant from the line 12 until the container 17 is heavy enough to overcome the counterweight returning the parts to the position where valve 15 is again closed. The beverage coils are located within the container 17 as in the case of the first described form.

In Fig. 7 we have illustrated the use of our invention for the direct refrigeration of any desired space and not limited to a beverage cooler. In this instance, a closed housing 67 of any shape desired encloses a reservoir 68 which contains liquid refrigerant 69 up to any suitable level, such as 70. Above this level the reservoir 68 is filled with vaporized refrigerant in the space 71. In

the central portion of the reservoir is an upstanding hollow column 72, the upper end of which carries a bracket 73 which engages the longer arm of lever 74 which is pivoted at 75 on a fixed bracket 76. The shorter end of lever 74 is pivotally connected at 77 to rod 78 which operates the refrigerant admission valve 79. Refrigerant enters through line 80 from the compressor-condenser unit which is like that previously described. A spring 81 is mounted within a sleeve 82 and counterbalances the weight of the reservoir 68 with its contents and connections. Line 83 leads back to the compressor and may be provided with a constant pressure valve 84, although in the case of a domestic refrigerator this constant pressure valve would probably be omitted. Such devices are usually constructed of such a size and capacity that when filled to normal level with refrigerant the proper cooling effect will be produced.

The operation of the device of Fig. 7 should now be clear. The housing 67 is directly in the chamber to be cooled and refrigerant flows into the reservoir 68 until spring 81 is overcome, causing lever 74 to move in a counterclockwise direction until valve 79 is closed. When refrigerant has vaporized into the space 85 so that the weight of the reservoir 68 decreases, the spring 81 raises the reservoir so as to operate lever 74 to open valve 79 and admit more refrigerant. The vaporized refrigerant passes through line 83 back to the compressor.

In Fig. 8 we have shown how the weight of the refrigerant reservoir may be used directly to operate the refrigerant admission valve. Here the container 86 is entirely closed and normally has liquid refrigerant 87 up to a level 88 and above that the space 89 is filled with vaporized refrigerant. The reservoir 86 is mounted on a flexible bellows 90 supported on a fixed surface 91. A spring 92 may be provided, if desired, to aid the bellows 90 in supporting the reservoir 86. This spring is suitably guided both bottom and top and may be adjusted by means of nut 93 threaded on sleeve 94. The refrigerant admission pipe 95 communicates with the bottom of the bellows 90 and supports a fixed valve seat 96. Secured to the reservoir 86 is a needle valve 97 in position to coact with seat 96. Liquid refrigerant flows into the bellows and through opening 98 into reservoir 86. Vapor is removed from the space 89 through a pipe 99 which has a liquid-tight connection with the support 91 and a sliding connection 100 with reservoir 86. This pipe is thus held fixed as the reservoir 86 moves up and down. The pipe 99 is connected back to the compressor. A small hole 99a may be provided just above the normal level of liquid refrigerant so that when oil collects on top of the refrigerant it will be pumped back to the compressor. Suitable means is provided such as the fixed guides 101 for holding the reservoir 86 for free vertical movement.

The operation of the device of Fig. 8 should now be apparent. As more refrigerant enters the reservoir 86 it becomes heavier so as to overcome the bellows 90 and spring 92, causing valve 97 to close on its seat 96. As refrigerant vaporizes into the space 89 and is carried back to the compressor the reservoir becomes lighter until valve 97 is opened to admit more liquid refrigerant.

Fig. 8 illustrates an automatic defrosting arrangement. When the reservoir 86 is directly exposed to the cooling chamber a coating of frost 102 will form on the outer walls thereof. This

adds to the weight of the reservoir 86 and, when the accumulation of frost has become sufficiently great, the amount of refrigerant 87 will gradually decrease as the weight of the frost closes valve 97 earlier than would otherwise be the case. When the amount of refrigerant in the reservoir 86 is cut below a certain point the reservoir and the space around it will become warmer so that the frost 102 will be melted off the outside of the reservoir 86. When this occurs the normal 10 amount of liquid refrigerant will again be necessary within the reservoir 86 to overcome the counterbalancing bellows and spring so that the device will again cool as originally intended.

In the modification of Fig. 9, a reservoir 103 holds liquid refrigerant 104 in the lower portion thereof and vaporized refrigerant in the space 105. Here the container is counterbalanced by the bellows 106 and spring 107 as described in connection with Fig. 8. The refrigerant admission line 108 supports a fixed valve seat 109 which cooperates with needle valve 110 in the same fashion as described in Fig. 8. The line 111 leading back to the compressor is here connected directly to the top of reservoir 103 by means of a flexible connection 112. If this device of Fig. 9 were like that of Fig. 8 the forces acting to open and close the valve 110 would be very slight, namely, the weight of the reservoir 103 and a few pounds of refrigerant inside the same. This might not be sufficient to overcome the flexible connection 112 so as to give efficient operation. We have therefore provided a very strong spring 107, say exerting a force of one hundred pounds upwardly from the fixed support 113. We then provide another strong spring 114 acting downwardly from the fixed support 115 against the reservoir 103. This spring 114 may exert a force say of ninety-nine pounds. These strong springs overcome the resistance of the flexible connection 112 very easily so that the movement of reservoir 103 is not hampered in any way. It therefore takes only one pound difference in the weight of liquid refrigerant indicated at 104 to operate the valve 110. In other respects, this device operates like that of Fig. 8.

In Fig. 10, we have shown an arrangement whereby the refrigerant container is given a mechanical advantage for operating the refrigerant admission valve. Here the reservoir 116 has liquid refrigerant 117 in the lower portion thereof and vaporized refrigerant in the space 118 above. The line 119 is connected directly to the reservoir to conduct vaporized refrigerant back to the compressor. A flexible connection 120 is provided in this line. The liquid refrigerant communicates through pipe 121 at the bottom of the reservoir to a fitting 122 attached to the bottom of closed bellows 123 which is mounted on the fixed support 124. The refrigerant admission pipe 125 supports a fixed valve seat 126. The fitting 122 supports needle valve 127 for cooperation with the seat 126. The pipe 121 is pivotally mounted at 128 on a fixed bracket 129. A spring 130 is held in compression between the support 124 and pipe 121 so as to normally urge valve 127 in opening direction.

It will now be apparent from consideration of Fig. 10 that the reservoir 116 working on a long lever arm about the pivot point 128 will provide any desired mechanical advantage through the shorter lever arm to close the valve 127. As the refrigerant 117 vaporizes, the reservoir 116 becomes lighter until spring 130 overcomes the weight of the reservoir and opens valve 127 to

75 admit more liquid refrigerant. When the balance is again restored, the weight of the reservoir is sufficient to close valve 127.

In Fig. 11 we have illustrated at the right-hand end thereof a reservoir 86' constructed, supported and operated in all respects exactly like the reservoir 86 of Fig. 8 except for the liquid refrigerant connection 131. This leads through a flexible connection 132 and suitable piping 133 and 134 to the lower portion of closed containers 134 and 135. The reservoir 86' is filled with liquid refrigerant up to the level 88 and, through the equalizing connections 131 and 133, the liquid will then be at the same level in the containers 134 and 135. The pipe 99 for leading vaporized refrigerant back to the compressor is connected to a manifold 136 which in turn is connected at 137 and 138 to the upper portion of containers 135 and 134, respectively. Thus, vaporized refrigerant is conducted from the spaces 139 and 140 back to the compressor.

The operation of the equipment shown diagrammatically in Fig. 11 should now be clearly understood. The containers 134 and 135 may be located in separate cooling chambers where each provides its own cooling effect while being controlled from a single reservoir 86'. As the liquid refrigerant in the reservoir 86' becomes reduced by vaporization, the bellows 90 and spring 92 serve to lift the reservoir so as to open valve 97 and admit more refrigerant to reservoir 86. and at the same time, to the containers 134 and 135. The reservoir 86' is permitted to move up and down by the flexible connection 132. When it becomes heavy enough it will then overcome the bellows 90 and spring 92 to close valve 97 cutting off the admission of liquid refrigerant.

In Fig. 12 we have shown a device which is operable by snap action. Here the container 141 is adapted to hold liquid refrigerant in the lower portion thereof at 141a up to a level indicated at 142 which will vary somewhat according to the teachings of this invention. Above this level the upper portion 141b is filled with vaporized refrigerant. A flexible conduit 143 is connected back to the compressor as in previous forms of our device. The admission of liquid refrigerant to the lower portion of the container is through line 144, valve 145 and flexible line 146. The major portion of the weight of the container 141 and its contents and connections is balanced by a spring 147 which is supported on a fixed base 148. The container is rigidly connected with the longer arm 149a of a bell crank which has a fixed pivot at 150 on a fixed bracket 151. The short arm of the bell crank 149b has a pin and slot connection 152 with a link 153 which is pivotally mounted at 154 on the fixed bracket 155. A link 156 is pivotally connected at 157 with the link 153 and is pivotally connected at 158 with the valve 145. A spring 159 is connected between pin 157 and a fixed pin 160 on the fixed base 161. The operation of this form of our device should now be apparent. With the parts in the position shown in Fig. 12, enough refrigerant has vaporized to lighten the container 141 so that it is moved upwardly urged by spring 147 so as to open valve 145 and admit additional liquid refrigerant to the space 141a. As the container becomes heavier, due to the admission of liquid refrigerant, it will move downwardly carrying the bell crank arm 149 in a clockwise direction about the pivot 150. This will carry link 153 toward the right, as viewed in Fig. 12, until spring 159 passes 70 to the right of the pivot 154, after which, the

link 153 will move in a counterclockwise direction with a snap action, this movement being permitted by the pin and slot connection 152. This will close the valve 145 stopping the flow of refrigerant. When refrigerant has vaporized into the space 141b so that the container becomes lighter, it will be urged upwardly by spring 147 which will carry the bell crank arm 149b in a counterclockwise direction, at which time, the pin 152 will move to the left-hand end of the slot 152a. A slight movement of arm 149b in a counterclockwise direction will then carry spring 159 slightly to the left of pivot 154 substantially as shown in Fig. 12, whereupon spring 159 will open valve 145 with a snap action which is permitted by the pin and slot connection.

What we claim is:

1. In a device utilizing a vaporizable refrigerant, the combination of chamber means for containing refrigerant vapor, a reservoir for liquid refrigerant in said chamber means, said reservoir being mounted for vertical movement as its weight becomes lighter or heavier, a liquid refrigerant supply for said reservoir including a control valve therefor, an operative connection between said reservoir and said valve for opening and closing said valve respectively by rise and fall of said reservoir, counterbalancing means operatively connected with said reservoir for causing the latter to rise when the weight of said reservoir and its content of liquid refrigerant is less than a predetermined amount, and fluid cooling coils in said liquid refrigerant within said reservoir.

2. In a device utilizing a vaporizable refrigerant, the combination of chamber means for containing refrigerant vapor, a reservoir for liquid refrigerant in said chamber means, said reservoir being mounted for vertical movement as its weight becomes lighter or heavier, a liquid refrigerant supply for said reservoir including a control valve therefor, an operative connection between said reservoir and said valve for opening and closing said valve respectively by rise and fall of said reservoir, counterbalancing means operatively connected with said reservoir for causing the latter to rise when the weight of said reservoir and its content of liquid refrigerant is less than a predetermined amount, there being a recess in said reservoir cooled by said refrigerant, and a fluid flow tank positioned in said recess.

3. In a device utilizing a vaporizable refrigerant, the combination of chamber means for containing refrigerant vapor, a reservoir for liquid refrigerant in said chamber means, said reservoir being mounted for vertical movement as its weight becomes lighter or heavier, valve means for controlling refrigerant flow and responsive to reservoir movement, there being an opening provided leading out of said reservoir at approximately the top level of liquid refrigerant in said

reservoir, whereby to drain off oil floating on said liquid refrigerant, and a drain leading out of said chamber means below said opening for removing said oil.

- 5 4. In a device utilizing a vaporizable refrigerant, the combination of chamber means for containing refrigerant vapor, a reservoir for liquid refrigerant in said chamber means, an inlet for liquid refrigerant leading directly into said reservoir, said reservoir being mounted for vertical movement as its weight becomes lighter or heavier, means counterbalancing the weight of said reservoir and contents, valve means for controlling refrigerant flow through said inlet and having an operative connection with said reservoir, whereby said valve means is responsive to reservoir movement, said counterbalancing means being so chosen as to be overcome by the weight of said reservoir when less than completely filled with liquid refrigerant, whereby said valve means is closed and said chamber means outside of said reservoir remains substantially free of liquid refrigerant.
- 10 5. In a device utilizing a vaporizable refrigerant, the combination of chamber means for containing refrigerant vapor, a reservoir for liquid refrigerant in said chamber means, an inlet for liquid refrigerant leading directly into said reservoir, said reservoir being mounted for vertical movement as its weight becomes lighter or heavier, means counterbalancing the weight of said reservoir and contents, valve means for controlling refrigerant flow through said inlet and having an operative connection with said reservoir, whereby said valve means is responsive to reservoir movement, said counterbalancing means being so chosen as to be overcome by the weight of said reservoir when less than completely filled with liquid refrigerant, whereby said valve means is closed and said chamber means outside of said reservoir remains substantially free of liquid refrigerant.
- 15 5. In a device utilizing a vaporizable refrigerant, the combination of chamber means for containing refrigerant vapor, a reservoir for liquid refrigerant in said chamber means, an inlet for liquid refrigerant leading directly into said reservoir, said reservoir being mounted for vertical movement as its weight becomes lighter or heavier, means counterbalancing the weight of said reservoir and contents, valve means for controlling refrigerant flow through said inlet and having an operative connection with said reservoir, whereby said valve means is responsive to reservoir movement, said counterbalancing means being so chosen as to be overcome by the weight of said reservoir when less than completely filled with liquid refrigerant, whereby said valve means is closed and said chamber means outside of said reservoir remains substantially free of liquid refrigerant.
